TRAP FOR INTRAVENOUS INJECTION APPARATUS

Clarence R. Bauer, Irvington, N. J.

Application July 7, 1949, Serial No. 103,351

3 Claims. (Cl. 128—214)

1

This invention relates to apparatus for the intravenous injection of medicinal liquids into the body. More particularly, the invention relates to an improved air and sediment trap for preventing undesirable materials from entering the body with the injected liquid.

Although various devices have long been known for intravenously injecting medicinal liquids into the body, the most widely practiced process is known as the gravity-flow method. In that method a hypodermic needle is connected by rubber tubing to a vessel containing the fluid to be injected. The vessel, which is usually provided with a flow-regulating cock, is suspended above the patient, and after the regulating cock, tubing and needle are completely purged of air, the needle is properly inserted into the patient's vein and the solution is allowed to flow by gravity into the vein.

In an alternative process, known as the pressure-flow method, the liquid supply is subjected to air pressure provided by a compressor such as a pressure bulb, plunger or the like. Combinations of the gravity-flow and pressure-flow systems are also employed.

With any of these systems, a section of transparent tubing, such as a glass tube, is usually included in the tubing between the needle and liquid supply vessel to enable the doctor or attendant to observe the passage through the tubing of air bubbles which may be entrained with the liquid. When air bubbles are observed in the transparent tubing, the injection needle must be withdrawn immediately from the vein, the supply line purged of the air bubbles, and the needle reinserted into the vein to continue the injection. This operation is time-consuming and often painful and dangerous to the patient. If air bubbles enter the vein with the injection liquid, an air embolus is produced, usually resulting in severe pain to the patient, and if allowed to continue even for several seconds, the patient may receive a dangerous or fatal amount of air. Even though a constant watch is maintained, it is not infrequent for a severe or fatal air embolus to develop within a matter of several seconds. The repeated purging of air from the tubing which connects the injection needle to the liquid supply results in a loss of valuable medicinal material, and as usually performed, the medicinal liquid is sprayed over the floor and equipment in the room where the patient is being treated.

The principal objects of this invention are to provide an improved trap for connection into the liquid supply line of an intravenous injection ap-

2

paratus for preventing the injection of air bubbles and other foreign materials with the injected liquid; to provide such a trap which is light in construction and designed for stable, upright attachment to the patient's arm or other body member; and to provide such a trap designed so as to eliminate the necessity of purging the supply line leading to the device.

Another object of the invention is to provide such a trap having sufficient capacity to trap therein all the air which normally becomes entrained in the liquid during the injection of a pint of liquid, a pint being the size in which injection liquids are usually supplied.

15 A further object of the invention is to provide such a device having a sediment trap as an integral part thereof.

These and other objects, novel features and advantages of the invention will become apparent 20 from the following description of the embodiment thereof illustrated in the accompanying drawing, in which:

Fig. 1 is a top plan view of a trap constructed in accordance with this invention; and

25 Fig. 2 is a vertical section taken along the line 2—2 of Fig. 1.

Referring to the drawing, the trap, which is advantageously made of glass or other transparent material such as the transparent plastic material 30 sold under the trade-mark Lucite, comprises a cylindrical or cylinder-like tube 4 with its upper and lower ends closed. A pair of tubes or necks 6 and 7 are connected to substantially opposite sides of tube 4 adjacent the lower end thereof 35 and communicate with the chamber 5 therein. The lower end of tube 4 is substantially flat as shown at 4a, and extends slightly below the bottom of tubes 6 and 7 to provide a sediment receiving chamber 5a. The flat bottom of tube 4 and the connection of inlet and outlet tubes 6 and 7 adjacent the bottom of tube 4, with a substantial angle between tubes 6 and 7, provide for 40 stably mounting the device on the patient's arm or other body member in an upright position by means of strips 8 of transparent adhesive tape or the like secured across tubes 6 and 7.

In use, inlet tube 6 is connected to the source 50 of the injection liquid by means of rubber or transparent plastic tubing 9 which is fitted over a protruding flange 6a on the exterior of tube 6. Outlet tube 7, having a flange 7a, is similarly connected directly to the hypodermic needle by means of a short section of tubing 10. With the bottle of injection liquid suspended above the patient, and with the trap connected thereto and

3

to the hypodermic needle as described, the trap will be filled initially with injection liquid 11 and it will be necessary only to purge the line between outlet tube 7 and the tip of the needle before inserting the needle into the patient's vein. This purging is readily accomplished by allowing a small amount of the liquid to flow through tubing 10 and through the needle.

Air bubbles 12 which are entrained with the liquid as it enters the trap rise within chamber 5 and displace some of the liquid from the upper end thereof as indicated in Fig. 2. Any foreign material 13 which is lighter than the liquid will also rise to the surface thereof within chamber 5 and will be retained in this chamber. Any foreign material 14 which is heavier than the liquid will settle into the sump 5a. Consequently, the liquid flowing out of chamber 5 will be entirely free of air bubbles and entrained solid materials.

While the trap operates entirely satisfactorily with the inlet and outlet tubes 6 and 7 connected to substantially opposite sides of tube 4, tubes 6 and 7 may be arranged with a smaller angle between them. For example, as shown in phantom at 17 in Fig. 1 the outlet tube may be disposed at an angle of less than 180°, but advantageously more than 90° with respect to the inlet tube. With the axes of the inlet and outlet tubes offset relative to each other, there is less chance that air bubbles or entrained solid material will be carried through the trap with the injection liquid, or that sediment deposited in the sump 5a will be washed into the outlet tube. When the angle between the inlet and outlet tubes is less than about 180°, a counter-balancing support rod or tube 16 as shown in phantom in Fig. 1 is advantageously connected to tube 4 to provide a completely stable support for the trap. Of course, the auxiliary support member 16 does not communicate with chamber 5.

I have found that the efficiency of the trap disclosed is at least partially attributable to the relative proportions of the chamber 5, the internal diameter of tubes 6 and 7, and the depth of sump 5a. In order for the air bubbles and other foreign material to be completely removed from the liquid within the trap, the ratio of the diameter of chamber 5 to the internal diameter of tubes 6 and 7 should be at least about 4 to 1, and the ratio of the depth of sump 5a below the bottom of tubes 6 and 7 to the internal diameter of tubes 6 and 7 should be at least about 1 to 2. In order to provide chamber 5 with sufficient capacity to accommodate safely the maximum amount of air which is normally entrained in a pint of injection liquid, when employing either the gravity-flow or pressure-flow systems described above, chamber 5 should have a volume of at least about 6 cubic centimeters above the top of tubes 6 and 7 as indicated by the line 15.

A trap such as shown in the drawing and which has proven highly efficient in service has the following dimensions:

	Inches
Internal diameter of chamber 5	1/2
Internal diameter of tubes 6 and 7	1/8
Depth of sump 5a below bottom of tubes 6 and 7	1/8
Dome height of tube 4 above line 15	1 1/8

The trap illustrated in the drawing is between two and two and a half times larger than the trap described, but the proportions are approximately those specified above.

With an air and sediment trap constructed according to this invention, the intravenous in-

4

jection apparatus, including such a trap, may be applied to a patient as described and the injection treatment may proceed without further attention on the part of the doctor or operator.

5 It will be unnecessary to maintain watch over the flow of the injection liquid or to remove the injection needle from the patient's vein to prevent entry of air bubbles or other material with the injection liquid, as air bubbles and solid 10 foreign materials which become entrained with the injection liquid will be removed automatically as they pass through the trap.

I claim:

1. In an intravenous injection surgical apparatus, an air and sediment trap comprising a transparent cylindrical tube disposed vertically and defining a chamber closed at its upper and lower ends and having an inlet neck and an outlet neck communicating with the chamber 20 within said cylindrical tube and adapted for connection in a supply line of the injection apparatus, said inlet and outlet necks being both disposed horizontally and connected to said cylindrical tube adjacent to and in slightly upwardly 25 spaced relation to the lower end thereof with a substantial angle between said inlet and outlet necks, and the lower end of said cylindrical tube having a substantially flat under surface whereby said trap is adapted for stable mounting in an upright position on a body member of the patient by application of adhesive tape across the inlet and outlet necks.

2. In an intravenous injection surgical apparatus, an air and sediment trap adapted to be 35 mounted in the liquid supply line of the intravenous injection apparatus, said trap comprising a transparent cylindrical tube disposed vertically and having its upper and lower ends closed and having an inlet neck and an outlet neck extending

40 horizontally and communicating with the chamber within said cylindrical tube in slightly upwardly spaced relation to the bottom thereof and adapted for connection respectively to portions of the liquid supply line between the source 45 of supply and the injection needle, said inlet and outlet necks being connected to said cylindrical tube adjacent the lower end thereof with an angle of more than about 90° and less than about 180° between said inlet and outlet necks, there 50 being a counterbalancing support member connected to said cylindrical tube adjacent the lower end thereof in the horizontal plane of the said necks, and the lower end of said cylindrical tube being substantially flat, whereby said trap is 55 adapted for stable mounting in an upright position on a body member of the patient by application of adhesive tape across the inlet and outlet necks.

3. In an intravenous injection surgical apparatus, an air and sediment trap comprising a transparent cylindrical tube disposed vertically and having its upper and lower ends closed, said tube having an inlet neck and an outlet neck adapted for connection in a supply line between

60 the source of supply and the injection needle of the apparatus, said necks being disposed horizontally and connected to said cylindrical tube adjacent the lower end thereof in slightly upwardly spaced relation thereto and communicating 65 with the chamber therein above the bottom of the chamber, said inlet and outlet necks being of a great deal smaller diameter than the cylindrical tube and extending from the cylindrical tube at an angle of more than about 90° and less than about 180° therebetween, and the lower port-

tion of the cylindrical tube below said inlet and outlet necks forming a sump for the collection of sediment.
